WINDOW FRAME

Walker Floyd, Richmond, Ind.

Application May 11, 1950, Serial No. 161,342

1 Claim. (Cl. 189—75)

1

This invention relates to a window frame and more particularly to a metal window frame.

The primary object of this invention is to enable an existing building to be equipped with metal window frames without requiring the cutting away of parts of the building or deforming a frame in order to fit the frame into a window opening.

Another object is to enable a window frame to be fitted into an existing window opening with but a minimum of labor and expense.

A further object is to fit the frame across walls of varying thickness and to assure a weather tight junction between the frame and the walls and between the separable elements of the frame.

The above and other objects may be attained by employing this invention which embodies among its features an inner frame member adapted to enter a window opening from the inner side thereof, an outer frame member adapted to enter the window opening from the outer side thereof, said frame members having flanges which project into the window opening and lie in overlapping relation therein and fastening means extending through said flanges and into the walls of the window opening.

Other features include spacers between the overlapping flanges, said spacers being held in place by the fastening means, and a lintel of fastener penetrable material carried by the inner frame member.

In the drawings:

Figure 1 is a fragmentary side view of the outside of a wall having a window opening therein equipped with this improved window frame;

Figure 2 is a view similar to Figure 1 of the inside of the wall;

Figure 3 is an enlarged horizontal sectional view taken substantially along the line 3—3 of Figure 2;

Figure 4 is an enlarged vertical sectional view taken substantially along the line 4—4 of Figure 1;

Figure 5 is an enlarged vertical sectional view through the top of the frame, and

Figure 6 is a fragmentary sectional view through a corner of a frame member showing a typical method of joining the vertical and horizontal elements of the frame members.

Referring to the drawings in detail a wall 10 is formed with a window opening 12 which in the present instance is shown as being defined by timbers 14.

Fitted into the window opening 12 from the outside thereof is an outer rectangular frame

designated generally 16 having an attaching flange 18 which lies against the timbers 14 defining the window opening 12 intermediate the inner and outer sides thereof. Carried by the attaching flange 18 along the edge thereof nearest the outside of the window opening is a spacing flange 20 which projects into the window opening 12 in perpendicular relation to the attached flange 18. Carried by the spacing flange 20 along the edge thereof remote from the attaching flange 18 is an inclined flange 22 which slopes toward the outer side of the wall 10 and carries at its outer marginal edge a facing flange 24. This facing flange overlies the outer side of the wall 10 in the immediate vicinity of the window opening 12. Suitable fasteners 26 are driven through the facing flange 24 into the wall 10 adjacent the edge of the flange 24 remote from the inclined flange 22 and similar fasteners 27 are driven through the attaching flange in order to secure the frame 16 in place in the window opening 12.

Entering the window opening 12 from the inside thereof is an inner rectangular frame member designated generally 28 having a base flange 30 which lies against the timbers 14 adjacent the inner edges thereof. Carried by the base flange 30 along the marginal edge thereof remote from the inner side of the window opening 12 is a stop flange 32 which lies perpendicular to the base flange 30 and extends into the window opening 12 in parallel relation to the spacing flange 20. A cover flange 34 is carried by the stop flange 32 at the edge thereof remote from the base flange 30 and projects toward the outer side of the window opening in spaced overlapping relation to the attaching flange 18 of the outer frame 16. A suitable filler strip 36, preferably of wood, is disposed between the attaching flange 18 and the cover flange 34 near the spacing flange 20 and extending at spaced points through the cover flange 34, filler strip 36 and attaching flange 18 into the timbers 14 are fasteners 38. Carried by the base flange 30 at the edge thereof remote from the stop flange 32 is a finish flange 40 which overlies the inner side of the wall 10 in the immediate vicinity of the window opening 12 and suitable fasteners 42 are driven into the wall 10 through the finish flange 40 adjacent the edge thereof remote from the base flange 30.

In the preferred form of the invention, the finish flange 40 is omitted from the frame 28 along the portion of the base flange 30 which lies against the top timber 14, and substituted for said omitted portion of the finish flange 40 is a

lip 44 which projects beyond the inner side of the wall 10 and supports a lintel 46 which is formed of a fastener penetrable material such as wood. As illustrated in Figure 4 this lintel overlies the inner side of the wall 10 immediately above the window opening 12 and is secured to the lip 32 by suitable fasteners 48.

A finish strip comprising an angle bar designated generally 50 lies along each side of the frame with one leg 52 lying between the filler strip 36 and the spacing flange 20 while the opposite leg 54 overlies the cover flange 34 and is pierced at spaced intervals to receive the fasteners 38. This leg 54 serves to conceal elongated openings 56 which are formed in the cover flange 34 and through which the fasteners 38 extend.

In use the outer frame member 16 is entered into a window opening 12 with the attaching flange 18 engaging the timbers 14 which define the window opening. The outer frame member 16 is pushed inwardly into said opening 12 until the facing flange 24 lies against the outer side of the wall 10. The fasteners 26 are then driven through the flange 24 to hold the outer frame member 16 in place. The spacer 36 is then placed in the window opening 12 in contact with the attaching flange 18 and in closely spaced relation with the spacing flange 20. The inner frame member 28 is then put in place by entering the base flange 30 into the window opening 12 from the inner side of the wall and advancing the cover flange 34 toward the spacing flange 20 and over the filler strip 36. When the finish flange 40 engages the inner side of the wall 10, it is secured in place by driving the fasteners 42 therethrough and into the wall 10. The finish strips 50 are then placed in position with the legs 52 thereof lying between the spacer 36 and the spacing flange 20 and the legs 54 thereof overlying the cover flange 34 to conceal the elongated openings 56 therein. The fasteners 38 are then passed through the spaced openings formed in the legs 54 of the finish strips 52 and through the elongated openings in the cover flange 34. These fasteners 38 continue on through the filler strip 36 and attaching flange 18 into the timbers 14 defining the window opening 12. Obviously the elongated openings 56 allow for limited movement of the inner frame member 28 so that the frame can be made to fit walls which vary slightly in thickness. A suitable calking compound 58 is applied to the frame at exposed junctions of the parts thereof and to the outer frame member 16 at its junction with the wall 10. Steel or wood casement windows may be mounted in the frame to open outwardly in any conventional manner and screens may be fitted in the inner frame member in abutting relation to the stop flange 32 and when so desired curtain fixtures may be attached to the lintel 46 either by entering nails or screws therein.

While in the foregoing there has been shown and described the preferred form of this invention, it is to be understood that minor changes in the details of construction, combination and

arrangement of parts may be resorted to without departing from the spirit and scope of the invention as claimed.

I claim:

- 5 In a metal frame for use in window openings of wooden buildings, an outer section, an intermediate section and an inner section, said outer section comprising a facing flange secured against the outer wall of the building about the opening, 10 an inclined flange extending into the opening from the inner edge of said facing flange, a spacing flange out-turned from the inner edge of said inclined flange and bearing edgewise against the framing of the opening; said intermediate 15 section comprising a spacer element having a flange lying against said framing and an out-turned flange abutted against the inner face of said spacing flange, and another flange in-turned from said out-turned flange and spacedly 20 overlying the first flange of the intermediate section; and said inner section comprising a second facing flange secured against the inner wall of the building about the opening, a relatively narrow base flange in-turned from the inner edge of 25 said second facing flange and bearing against the said framing, a second relatively narrow flange out-turned from the inner edge of said base flange, a second inclined flange out-turned from said second narrow flange, the free edge portion 30 of the latter inclined flange being horizontally disposed beneath the said another flange in flat abutted relation with respect thereto, screw fastenings passing through said facing flanges, the parallel flanges of said intermediate section and 35 the said horizontal edge portion of said second inclined flange, and a filler strip housed within the space between the first flange of said intermediate section and the said horizontal portions of said second section and disposed in abutted 40 relation with respect to the said out-turned flange of said intermediate section to prevent any bending of the said another flange and the said horizontal edge portion of the said second section, when the screw fastenings passing therethrough 45 and the filler strip are tightened.

WALKER FLOYD.
